[57] **CLAIM**

The ornamental design for a combined riflescope eyepiece housing and switch assembly, substantially as shown and described.

DESCRIPTION

FIG. 1 is a pictorial view of a combined riflescope eyepiece housing and switch assembly showing my new design;

FIG. 2 is a side elevational view thereof on a slightly reduced scale, the riflescope being shown in broken lines for illustrative purposes only, the opposite side being a mirror image with the exception of the screw head shown in FIG. 3;

FIG. 3 is a bottom plan view thereof on a slightly reduced scale;

FIGS. 4 and 5 are end elevational views thereof as seen respectively from the left and right sides of FIG. 2;

FIG. 6 is a top plan view of a second embodiment of my new design;

FIG. 7 is a side elevational view of the second embodiment of my new design.

The knurling on the rings shown in FIGS. 4 and 5 is shown only in part for convenience of illustration.
